GEORGE A. HILL AND CONRAD LOHNEs, OF SPRINGFIELD, OHIO, ASSIGNORS
TO THEMSELVES AND JAMES M. HARNER, OF DONNELSVILLE, OHIO.

Letters Patent No. 64,670, dated May 14, 1867.

SEED-PLANTERS.

The Schedule referred to in these Letters Patent and making part of the same.

TO ALL WHOM IT MAY CONCERN:

Be it known that we, GEORGE A. HILL and CONRAD LOHNEs, of Springfield, in the county of Clark, and State of Ohio, have invented a new and useful improvement in Seed-Planters; and we do hereby declare that the following is a full, clear, and exact description of the same, reference being had to the annexed drawings, in which—

Figure 1 is a perspective view.

Figure 2 is a plan.

Figure 3 is a central vertical longitudinal section; and

Figure 4 is a similar section through one of the seed-boxes.

The same letters are employed in all the figures when indicating the same parts.

A is the frame of the machine. This frame is made in two corresponding parts, forming the two similar sides of the machine. The frames are joined at A' in the middle of the end-pieces, which are each cut away one-half of their diameter, and arranged to overlap, sliding out and in through the bands B B, which are attached respectively to the ends of the end-pieces, sliding over the other piece. The bands B' remain in the middle of the frame, and have holes in them to receive the pins C, which pass through the end-pieces, holding them in any required position. This arrangement of the frame permits it to be arranged to plant in wider or narrower parallel rows, as required. The wheels D and D¹ are placed on each side of the frame. The wheel D¹ has on its inner face a series of holes to receive pins D³, which may be adjustably arranged to actuate the seed-valves, according to the requirements of the work. Scrapers, D², are attached to the frame to scrape off the earth which may adhere to the wheels. These pins as they revolve strike against the lever E, which is pushed thereby towards the seed-hopper. As soon as the pin disengages the lever it is quickly brought back by the spring E', acting upon a rod attached to the lever E, and parallel thereto. The seed-valves F F¹ are flat pieces passing under the hoppers, having a hole through each to receive the grain. These boards may be made in sets of different-sized holes, according to the size of the grain to be deposited, and the number to be placed in each hill, as the number of grains the openings will contain depends upon the sizes of the holes. The lever E is connected directly with the valve F by the pin F². The valve F¹ is actuated by the compound lever G, which consists of two levers joined at their ends, and respectively turning upon pivots near their centres, passing through elongated openings in the levers. The pins F² are fastened to the valves F and F¹ respectively, and pass through curved slots near the outer end of the compound lever G, which permit the width of the frame to be adjusted without interfering with the action of the seeding apparatus. H is a connecting-bar, extending from the junction of the two pieces of the compound lever back to the vertical hand-lever I, placed immediately in front of the driver's seat K. By means of this lever the driver may actuate the seeding mechanism if desired, or by drawing the lever back into a slot in the end of the seat, where it may be secured by the hook I', thus preventing the action of the seeding mechanism. The seat K is placed longitudinally between the wheels, and, by sitting back or forward upon it, the driver may regulate the depth of the ploughs according to the character of the ground. L is the grain-hopper, one being placed on each side. The valves F and F¹ pass under the hoppers, and when the hole in the valve is under the hopper it will be filled with grain. When the valve is drawn back this opening passes under the lip L', which extends from the bottom behind the hopper, and immediately over the valve. The seed being drawn over a hole falls through the pipe M into the furrow made by the ploughs N. The ploughs are made with flooring sides, the points being nearly horizontal, and rising curving upwards towards the heel. At the heels on each side the shovels O are placed, being adjustably attached to regulate the depth of their cut so that they may be used for covering the seed, or entirely withdrawn when the ploughs are used merely for furrowing out. P is a lever attached to the frame, and passing below the flooring S, and having a quadrant-formed cam eccentrically attached to it. The tongue R is carried entirely under the machine, being attached to the frame at the rear end. The cam Q is immediately over the tongue, and does not touch it when the ploughs are in the ground; but when it is desired that the ploughs may be raised the lever P is drawn back, the cam Q pressing upon the tongue R, and as this is supported upon the

ecks of the horses it cannot yield, but the front part of the frame will be raised, lifting the ploughs above the ground. The tongue passes through a slot in the brace T, which is fastened to the front end of the frame, thus preventing any lateral action of the tongue. This brace is curved backward to its lower end, which is carried low enough to touch the ground, and prevent the ploughs taking too deep a hold, particularly on rising ground. This may also be accomplished by wheels set under the front of the frame if preferred.

What we claim as our invention, and desire to secure by Letters Patent, is—

1. The combination of the double-sided ploughs, curving upward from near the point to the heel, and the bovcls O adjustably attached thereto, substantially as and for the purpose set forth.
2. The combination of the wheel D¹, adjustable pins D³, lever E and spring E', substantially as described.
3. The combination of the lever E, valves F and F¹, and pins F², with the compound lever G, having curved lots G' in the outer ends, substantially as set forth.
4. The combination of the compound lever G, valves F and F¹, connecting-bar H, lever I, hook I', and driver's seat K, substantially as described.
5. The combination of the driver's seat K, lever P, cam Q, and tongue R, substantially as set forth.
6. The combination of the tongue R, attached to the rear of the frame, and the brace T, attached to the front thereof, and constructed and arranged to operate substantially as set forth.

In testimony whereof we have signed our names to this specification in the presence of two subscribing witnesses.

GEORGE A. HILL,
CONRAD LOHNES.
